UNITED STATES PATENT OFFICE.

WILLIAM PATRICK POWER, OF NEWCASTLE, NEW SOUTH WALES, AND ESSINGTON LEWIS, OF MALVERN, VICTORIA, AUSTRALIA, ASSIGNEES TO THE BROKEN HILL PROPRIETARY COMPANY, LIMITED, A CORPORATION OF VICTORIA, AUSTRALIA.

BLAST FURNACE.

Application filed January 20, 1927, Serial No. 162,265, and in Australia December 9, 1926.

This invention relates to improvements in blast furnaces and refers more especially to blast furnaces for the smelting of iron ores.

The brickwork lining of blast furnaces is subject to considerable wear due to attrition from the ore and other materials passing downwards and this wear is usually more acute at the top or upper part of the furnace usually known as the shaft. With a view to avoiding this wear it has been customary to provide armor plating arranged upon the inside of the brickwork at the top or upper part of the furnace.

This armor plating has previously been supported either by being hung from the top, in which case the lining itself carries no portion of the weight, or by being built into the top lining, in which case the weight of this armor plating in addition to the weight of the top lining itself is supported by the lower lining of the furnace.

This armor plating applied to the top brickwork of the furnace in ordinary blast furnaces for smelting of iron ores requires the use of some sixteen tons or more of steel plates and it has been found that in the latter case this additional weight carried upon the brickwork of the furnace alone has a tendency to make the brickwork of the mantle bulge especially when the same is subject to the softening effect of the high temperatures which exist in that part of the furnace.

Consequently in practice it has been found that renewal of the brickwork is required more frequently at the lower part of the furnace than at the top, and when such re-lining is being effected it has been necessary to practically dismantle the whole of the furnace, causing the same to be out of commission for a considerable period.

Now the object of this invention is to provide means whereby one portion of the brickwork lining may be removed and renewed without affecting the other part or parts and also means for supporting the armor plating at the top of the furnace independently of the lower lining.

We accomplish these objects by forming the lining within the furnace shell of two or more (preferably three) independent parts and providing supporting means for the top portion of the lining connected to the shell of the furnace.

With this arrangement most of the wear

on the furnace lining takes place in or about the region of the melting zone, that is to say within the mantle or lower part of the in-wall, and a great saving may be effected both in time and material by having the top lining supported independently of the rest of the lining, allowing of the removal and replacement or renewal of the lower brickwork without disturbing the top portion of the lining whilst furthermore by eliminating the crushing load upon the brickwork or lower mantle of the furnace a longer life thereof is ensured.

Referring to the drawings, which illustrate merely by way of example a suitable embodiment of the invention:

Figure 1 is a vertical section.

Figure 2 is a horizontal section on the line 2—2 of Figure 1.

Figure 3 is a horizontal section on the line 3—3 of Figure 1.

Figure 4 is a vertical section on the line 4—4 of Figure 3 on an enlarged scale.

Figure 5 is a view in perspective of an armor plate element same scale as Figure 4.

Similar numerals refer to similar parts throughout the several views.

The furnace comprises an outside metallic shell 6 having an inner lining of brickwork. This inner lining is formed in sections (preferably three) which are independently supported, that is to say, the belly or centre portion 7, the upper in-wall 8 and the bosh or lower portion 9.

The lining in the bosh 9 is supported on the foundations of the furnace, the belly or centre portion 7 is supported on the columns 10 whilst the upper in-wall 8 is supported on a series of brackets 11 arranged around and attached to the outer shell 6 of the furnace. By means of this arrangement these three sections are independently supported and may be removed for repair or renewal purposes independently of each other, thereby effecting a considerable saving in time and labor.

The upper in-wall 8 is provided with a series of armor plates 12 for the purpose of protecting the same from wear from the passage of the raw materials fed in at the top of the furnace. These armor plates 12 are preferably shaped as shown in Figure 5 having downwardly projecting flanges 13 on their inner ends and upwardly projecting

flanges 14 on their outer ends or vice versa. These plates 12 are arranged radially and are embedded entirely in the brickwork of the lining except the exposed flanges 13 and are 5 arranged with relation to each other with the flanges 13 in substantial contact with the adjacent flanges on each side and above and below so that the assembled flanges 13 form a practically continuous metallic wall or armor for the lining of the upper in-wall 8. The top lining or in-wall 8 together with the armor plates 12 is superimposed upon an annular plate 15 having annular angle iron rings 16 and 17 which are bolted or otherwise secured to the series of brackets 11. These brackets 11 are bolted or otherwise secured to the outer shell 6 of the furnace. The angle iron rings 16 and 17 and the brackets 11 are preferably embedded in the 20 brickwork of the lining as shown in Figures 3 and 4. By the use of these brackets 11 the weight of approximately one-third of the furnace lining plus the weight of the armor plating is removed from the brickwork of the belly of the furnace below it. This ensures the running of the furnace for a longer period without the danger that the weight above will crush or weaken the lining below, whilst furthermore the lining in the belly of 25 the furnace or in the bosh as the case may be 30

may be torn out and repaired or renewed without disturbing the top lining.

We claim:

1. In a blast furnace, the combination with an upper lining of means for supporting the same connected to the outer shell of the furnace independently of the lower lining. 35

2. In a blast furnace, the combination with an upper lining having armor plating of means for supporting the same connected to the outer shell independently of the lower lining. 40

3. In a blast furnace, the combination with the furnace of a top lining and a lower lining, and a series of brackets secured to the shell for supporting the top lining. 45

4. In a blast furnace, the combination with the furnace shell of a top lining and a lower lining, and a series of brackets secured to the shell and a ring plate for supporting the top 50 lining. 50

5. In a blast furnace, the combination with the furnace shell of a top lining and a lower lining and a series of brackets secured to the shell and a ring plate and angle rings for 55 supporting the top lining.

In witness whereof we hereunto affix our signatures.

WILLIAM PATRICK POWER.
ESSINGTON LEWIS.
